MIXING DEVICE

Carl A. Madsen, San Diego, Calif., assignor, by direct and mesne assignments, of one-tenth to George R. Baird, San Diego, Calif., and eight-tenths to Jens Madsen, San Diego, Calif., and one-tenth to Richard T. Galatas, Long Beach, Calif.

Application April 18, 1938, Serial No. 202,721

9 Claims. (Cl. 225—26)

My invention relates to mixing devices and its objects are, to create in copious quantities carbonated beverages or water without the necessity of the application of the usual attendant pressures; to avert the danger from the production and storage of possibly explosive mixtures due to sudden changes of temperature or confined pressures; to provide a cheaper and handier form of construction for the production of carbonated waters; to carbonate fresh fruit juices immediately upon their production from the fruit; to stabilize the production of effervescent mixtures and to prevent deterioration thereof, particularly when exposed to the air; to afford a better means for the dispensing and distribution of effervescent waters, beverages and medicines, and generally, without the necessity of employing expensive apparatus, to afford an effective and simple means for producing carbonization of fluids at the time and place desired.

As is well known, siphon bottles or containers of carbonated beverages are very susceptible to any substantial changes in temperature, and in order to guard against explosions and the spraying of glass upon persons in their immediate vicinity, must always be kept at a low temperature. With any rapid rise in temperature, the amount of pressure upon the walls of the closed receptacle is increased, and if such rise is continued the internal pressure will shortly reach a point where an explosion will inevitably take place. Especially is this true where the contents of the bottle have been frozen, in which case great care should be used when such bottle is thawed. Should it be placed under the hot water faucet, or in the vicinity of a heater or stove, and the thawing not accomplished gradually, an explosion is likely to result. Each of the siphon bottles now in commercial circulation ordinarily carries a pressure well over a hundred pounds, and is therefore potentially a source of danger. Many accidents, according to the reports of industrial accident commissions, can be traced to this cause, and will continue to happen unless proper precautions are taken. Then again, in the case of any carbonated beverage contained in a bottle or other container, the gas therein contained tends to seep out with the passage of time, so that with the expiration of a few years after carbonization, there will be little or no effervescence upon the opening of the bottle.

With the operation of my improved device, however, there is no danger of explosion whatever. In the actual production of carbonated water at no time is it my purpose to confine the

charged fluid in a closed receptacle. The desired carbonization I effect as needed, without the application of the usual pressures, and without the use of high pressure tanks, metal capsules or the like. Through the use of my device, carbonated water is manufactured on the spot, and in the quantities desired. For immediate use it is especially designed to be used in dispensing beverages at a soda fountain or liquor counter, where potable liquors are combined with effervescent waters in the form of mixed drinks, and where it is very desirable to have at hand an unlimited supply of such waters. Being manufactured or composed as needed, there is no possibility of deterioration, or explosion.

Attention is hereby directed to the drawings in which similar numerals of designation refer to similar parts throughout the several views, and in which—

Figure 1 is a perspective view of one form of my improved device, showing the same in its usual upright position;

Figure 2 is a plan view of the same;

Figure 3 is a horizontal section on line 3—3 of Figure 1, looking in the direction of the arrows;

Figure 4 is a horizontal section on line 4—4 of Figure 1, through the faucet there shown looking in the direction of the arrows;

Figure 5 is a perspective view of a modification of my invention;

Figure 6 is a perspective view of a modification of my invention showing the same in the form of a rectangular box;

Figure 7 is a longitudinal section of a magazine cap designed as a cover and filler for my improved receptacle; and

Figure 8 is a section on line 8—8 of Figure 7 looking in the direction of the arrows.

Referring to the drawings, I preferably construct my improved apparatus of metal, glass, enamelware, clay products or other suitable material or substance upon which tartaric, citric or other acid bases have no deleterious effect. The main body 8 is constructed with the central septum 9, vertically disposed at right angles to the base 10 and dividing the chamber 11 into dual compartments A and B, which are of like capacity and volume and extend the entire length of said chamber. At the top of the chamber 11, is located the dam plate 12, partially covering the same, the function or purpose of said plate being to dam back or hold in check the fluids contained in compartments A and B. Back of the dam plate 12, I locate the dual openings 13 and 14,

to permit the ready introduction of carbonated water producing substances.

Preferably near the top of my device, at the front thereof, for the purpose of evacuating the fluids therein contained in equal amounts, is located the nose or spillway 15, divided into two sub-compartments A' and B' divided by the common septum 9. At the bottom of each sub-compartment A' and B' are the orifices 16 and 17, which are of equal diameter or open area in cross section and communicate with the compartments A and B respectively, and permit the discharge of their contents in equal amounts.

If desired, an additional dual outlet may be provided at the bottom of my device in the form of the faucet or valve 18, having substantially the same construction so far as concerns ducts or outlets as the nose 15, except for the valve closure or plug 19. As is obvious, this faucet or valve construction 18 could be substituted for the nose 15, or the apparatus provided with only one of these discharge openings and the other dispensed with.

In Figure 5, I have illustrated a modified form of my device, in which I have shown a single sheet of metal bent in the form of a wedge with the edges secured together at the line 20, the septum 9a serving to divide the chamber 11a into two equal compartments C and D similar to compartments A and B of Figures 1-4, and the edges of said septum 9a being similarly attached.

In Figure 6, I have shown another modification in which the chamber 11 is of rectangular construction, having compartments E and F, septum 9B, and faucet or valve 18a similar to the construction shown in Figures 1 and 4.

In Figures 7 and 8, I have shown a magazine cap or cover 22 which may be employed for the commercial dispensing of carbonated water, and which adds to the utility and better and more efficient operation of my invention. Such cover is provided with the rotating handle 21' having secured thereto the rotating post 23' to the lower end of which, and at right angles thereto, is attached the arm 23 arranged to rest and move upon the plate 30, said plate being preferably soldered or welded to the septum 9 and to the inner wall of the main body cylinder 8, and acting as a dam plate in the same manner as plate 12 shown in Figures 1 and 2.

A tablet magazine 24, constructed to receive a supply of tablets of bicarbonate of soda 25 and a tablet magazine 26 constructed to receive a supply of tablets 27 of tartaric or citric acid, are attached to the inner wall of the cap 22, and each extend downwardly nearly to the floor 30 of said cap, a space being left under the lower end of each magazine to permit the egress of a tablet upon contact with the arm 23. As will be observed, the tablets 25 are somewhat larger than the tablets 27, although each tablet is of the same thickness. In the floor 30, is the opening 28, which is of larger diameter than one of the tablets 25 and which is located in the path of the cup of the rotary arm 23, and permits the said tablet to descend therethrough into the chamber A upon being swept therein by said arm 23. In the floor also, is the opening 29 into the chamber B, which performs a similar office for the tablets 27. A groove 34 located near the edge of the cap 22 and shaped to engage with a corresponding groove in the cylinder 8, serves to keep the said cap in proper engagement with the compartments of said cylinder.

To operate my improved apparatus, I prefer-

ably first introduce through the aperture 13 into the compartment A a predetermined quantity of tartaric or citric acid and then add water in the proportion of 35 grains to 6 or 8 fluid ounces of water until said compartment is filled. I then introduce through the aperture 14 into the compartment B a predetermined amount of bicarbonate of soda or other alkaline substance and then add water in the proportion of 40 grains to 6 or 8 fluid ounces of water until the compartment is filled. These proportions may be varied in accordance with the amount of effervescence or carbonization desired; preferably, however, I find that the best results can ordinarily be secured by the employment of 10 parts of tartaric 15 or citric acid to 9 parts of bicarbonate of soda, each being in adequate solution in its individual compartment.

Thereupon, upon the container being tilted, or the contents discharged through the outlets provided, equal measured amounts will be simultaneously discharged or permitted to flow into the drinking receptacle through openings 16 and 17, said amounts beginning to mix immediately upon said discharge and continuing to mix upon reaching said receptacle, and to effervesce and to release carbonic acid gas in copious quantities thereafter. As will be observed, the septum 9 effectually prevents the mixture of the two fluids except as they actually come together after leaving the said spillway.

My invention may be embodied in other specific forms without departing from the spirit or essential characteristics thereof. The present embodiment, as above set forth, is therefore to be considered in all respects as illustrative and not restrictive, the scope of my invention being indicated by the appended claims rather than by the foregoing description, and all changes which come within the meaning and range of equivalency of the claims are therefore intended to be embraced therein.

What I claim and desire to secure by Letters Patent is:

1. In a mixing device, the combination of a fluid container, a partition located within said container and dividing the same into two compartments, and each of said compartments having at the top a separate discharge opening of equal cross sectional area to the other and located in proximity thereto, whereby the contents of said compartments may be discharged simultaneously in substantially equal amounts into a common receptacle.

2. In a mixing device, the combination of a fluid container, said container being divided into two compartments, each of said compartments having a separate discharge opening at the top thereof in proximity to the other and of the same cross sectional area, and a dam located adjacent to said openings for preventing overflow from said compartments while their contents are being discharged through said openings.

3. In a mixing device, the combination of a fluid container, said container being divided into two compartments, each of said compartments having an opening for the reception of fluids and other substances, a separate magazine for each compartment, and for dispensing tablets for mixing with the fluids of such compartment, and means for discharging said tablets from each magazine into its proper compartment, and means for discharging the contents of said com- 75

parts simultaneously into a common receptacle.

4. In a mixing device, the combination of a fluid container, a nose forming a spillway connected therewith and adjacent to the top thereof, a vertical partition secured within said container and dividing the same into two separate compartments, each of said compartments having a discharge opening communicating with said spillway, whereby the contents of each of said compartments may by tipping said container be discharged simultaneously in substantially equal amounts into a common receptacle.

5. In a mixing device, the combination of an elongated fluid container, a nose forming a spillway connected therewith and adjacent to the top thereof, a vertically disposed partition located within and secured to said container and dividing the same into two separate compartments of substantially equal size, each of said compartments having a discharge opening of the same cross sectional area and communicating directly with said spillway, whereby the contents of each of said compartments may by tipping said container be discharged simultaneously in substantially equal amounts into a common receptacle.

6. In a mixing device, the combination of a fluid container, a nose forming a spillway connected therewith and adjacent to the top thereof, a vertically disposed partition secured within said container and dividing the same into two separate compartments, each of said compartments having a discharge opening communicating with said spillway, and a dam plate affixed to the top of said container adjacent to said discharge openings for preventing overflow from said container when the said container is tipped and while the contents in whole or in part of said container are being discharged.

7. In a mixing device, the combination of a fluid container, a nose forming a spillway con-

nected therewith, a septum secured within said nose and dividing said spillway into two separate passageways, a partition secured within said container and dividing the same into two separate compartments, each of said compartments having a discharge opening communicating with one of said passageways, whereby the contents of said compartments may be kept separated and discharged simultaneously in desired amounts into a single receptacle.

8. In a mixing device, the combination of an elongated container, a nose forming a spillway connected therewith adjacent to the top thereof, a septum secured within said nose and dividing said spillway into two separate open passageways, a vertically disposed partition within said container and dividing the same into two compartments of substantially equal size, each of said compartments having a discharge opening of the same size communicating directly with one of said passageways, whereby part or all of the contents of said compartments may on tipping said container be discharged simultaneously into a common receptacle.

9. In a mixing device, the combination of an elongated fluid container, a nose forming a spillway connected therewith and adjacent to the top thereof, a septum formed within said nose and dividing said spillway longitudinally into two separated passageways, a vertically disposed partition within said container and dividing the same into two compartments, each of said compartments having an opening communicating directly with one of said passageways and having an opening at the top through which the contents thereof may be replenished, and a dam plate affixed to the top of said container to prevent overflow from said container when tipped to discharge a portion of the fluid contents of said container.

CARL A. MADSEN.
